UNITED STATES PATENT OFFICE

2,327,551

MOP HEAD AND FRAME THEREFOR

Floyd T. Petty, Westfield, Mass.

Application June 28, 1941, Serial No. 400,281

2 Claims. (Cl. 15—147)

This invention relates to improvements in cleaning implements and is directed more particularly to an improved mop-head construction and a frame therefor.

It is a principal object of the invention to provide a mop-head for association with a frame of the so-called swivel type to which a handle will usually be attached. As will appear, the invention includes a new frame or support and a novel mop, brush, duster or similar head removably attached thereto and removable therefrom and the same are so formed that the working part of the mop may easily take various angular positions relative to the line of direction in which the end of the handle is moving.

By reason of the novel construction of the invention, the mop may be more easily manipulated and moved over a floor surface and is particularly suitable for cleaning around and working at the areas about the feet of tables, chairs, desks, etc. That is to say, the mop-head construction is such that there is provided what may be called a recess for receiving the legs or feet of furniture and finger-like parts at opposite sides of the recess are arranged to engage opposite sides of whatever piece of furniture is engaged or embraced.

It is a further object of the invention to provide a mop-head device which includes a supporting frame and a body of some suitable flexible material having a plurality of so-called "thrums," which usually consist of threads or yarns, attached thereto and providing the dirt-collecting surfaces. As will be described, said body member is especially formed to have what may be termed a pocket for releasably receiving the new type of frame, the body and frame members being constructed for co-operative relationship and combinable into a working mop-head unit which is particularly adapted for cleaning around vertical or elongated members, such as legs of chairs, etc.

With the foregoing and various other novel features and advantages and other objects of my invention as will become more apparent as the description proceeds, the invention consists in certain novel features of construction and in the combination and arrangement of parts as will be hereinafter more particularly pointed out in the claims hereunto annexed and more fully described and referred to in connection with the accompanying drawing, wherein:

Fig. 1 is a top plan view of the mop-head device of my invention with dot-dash lines to show the outer boundary of the body thereof;

Fig. 2 is a top plan view of the supporting frame of the invention;

Fig. 3 is a sectional view on the line 3—3 of Fig. 1;

Fig. 4 is an enlarged sectional elevational view taken at one edge of the mop-head body; and

Fig. 5 is a more or less diagrammatic view to explain how the mop-head device of the invention may be manipulated with respect to a leg or foot of a piece of furniture.

Referring now to the drawing more in detail, the invention will be fully described.

The frame or supporting member of the mop-head device of the invention is indicated generally by 2. It is to be understood that its shape and size may vary as well as the material of which it is formed.

It, preferably, however, consists of a length of metal, either rod-like, as shown, or strip-like in nature which is bent to have spaced side rails 4. Said rails may be connected at adjacent ends by an end portion 6 of any desired shape or form.

The other end of the frame may likewise be variously formed but in any event it has a pair of spaced fingers, indicated generally by 8 with a transverse guard member 10 extending rearwardly or inwardly of the outer ends of the fingers. I have found that the simplest and cheapest way to manufacture the frame is to form it of a single length of rod with the fingers formed by bending the rod as shown and with the guard 10 integral with and connecting the inner arms of the fingers, all as shown.

This frame member 2 is adapted to carry a head member, indicated generally by 20, and this includes a support which is generally formed of some suitably flexible material, such as fabric, canvas, or the like, and a plurality of so-called thrums which extend outwardly from adjacent outer marginal edges of the support to form a mop-body. This head member 20 is formed to have upper and lower walls, 22 and 24 respectively, secured together adjacent marginal edges, as by stitching 26 or the like, so as to form a pocket therebetween.

The upper wall part 22 is provided with an opening therein which serves as an entrance to the pocket and this opening preferably is formed to have a relatively restricted and elongated neck-like part 28 leading into a more or less central and wider aperture 30.

Secured to and extending outwardly from the support are a plurality of so-called thrums 40 which usually will be threads or yarns and which

form a mop-body. They may be variously secured to the support but, when they consist of yarns or threads, they will preferably be looped or doubled intermediate their ends with their central portions secured to the member 20 as by stitching 42.

According to the invention, the yarns are stitched as at 42 or otherwise secured to the support 20 at a point inwardly of the marginal edges thereof, as shown in Fig. 4. Such a construction tends to provide a more flexible arrangement and the thrums, which, of course, do the actual cleaning work are both efficiently supported and disposed in such a way that their free ends are capable of performing an effective cleaning operation.

The fingers 8 of the frame are receivable in correspondingly finger-shaped parts of the body. That is to say, the pocket made by the two walls 22 and 24 is so formed and its parts are so spaced that when the frame is placed in the pocket by way of the continuous opening formed by slot 23 and hole 30, the fingers 8 fit into correspondingly formed pocket parts of the body. It is understood that the wall 22 is movable relative to wall 24 and is bound thereto along or adjacent inner marginal edges thereof, as previously described.

Where the frame member 2 is formed from a single length of rod-like material, the fingers 8 will be more or less U-shaped and may have somewhat rounded forward ends as shown. In any event they will be receivable within the arms of the U-shaped end of the body's pocket, with the total result that a frame-containing or supporting and thrum-carrying body or support is provided which has a U-shaped horizontally-extending recess R, as is shown, for receiving or engaging the sides of the leg or foot F of a chair, table, or the like.

I have found that most efficient results can be obtained when the thrums, which are indicated generally by T, extend from adjacent but inwardly of the edges of the body and that if those thrums T which extend from around recess R are relatively short as compared with those which are on the outer sides of the body. This is because it is not desirable that the thrums around recess R be so long as to become snarled together during use of the mop-head device; as is obvious, such snarling is more likely to happen when there is more definite inter-engagement of thrums as in the case of those around the recess which are more apt to become snarled because of the very fact that they are intended to be agitated more than others around and about elongated parts of furniture.

It is to be understood that the means of connecting a handle and the frame 2 may vary but, according to the form shown, there is a pivot member having end journal parts 54 in substantial axial alignment with and substantially at right angles to the rails 4. A stick or handle member (not shown) may be provided and this will be adapted to have its lower end attached to the offset or pivotal part 53 of the connecting rod which is bent into parallelism with rails 4 in the drawing.

In any event, the pivot member and handle are journalled so that the mop body and handle may assume various angular positions relative to one another when the device is in use.

There may be brackets 50 held against sliding movement relative to the rails 4, as by bending

and clamping the body parts of said brackets over the rails as indicated in Fig. 2. That is to say, the disposition and arrangement of the rails and brackets is such as to prevent relative movement thereof and hold the brackets in their desired oppositely-disposed relation.

The brackets have inwardly-extending end portions, each of which are provided with aligned slots or openings 52 spaced inwardly of their inner edges. The opposite end portions 54 of the pivot member or connecting member are journalled between said slotted and oppositely-disposed brackets 50, as indicated.

Preferably the opposite ends of the rod are headed, as at 56, and these heads are disposed in said slots 52. It is desirable that further strength and permanency be given the article by securing the said end parts of each clip or bracket 50 to the frame 2 as by riveting, welding, or otherwise.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. A mop for associating with a frame formed from a rod-like member to have spaced side members with one closed end and spaced fingers providing a recess at its other end and a transverse handle connector swivelled to said side members intermediate said ends comprising in combination, superposed upper and lower mop-forming walls of flexible material having spaced finger portions extending forwardly from one end thereof forming therebetween an outwardly opening recess at said one end of said walls, the walls being secured together at their marginal edges providing a main pocket and spaced finger pockets extending from an end thereof at opposite sides of said recess, said upper wall provided with a central opening spaced inwardly from the inner side of said recess and a slot connected to and extending longitudinally away from said opening to the opposite end thereof cooperating to facilitate insertion of a frame therethrough and into said pocket with the fingers thereof in said finger pockets and the handle connector thereof disposed below said central opening between opposite ends of the mop, and thrums extending from the marginal edges of said walls.

2. A mop construction comprising in combination, a frame and a mop body, said frame formed from rod-like material to have side members with spaced fingers at one end thereof extending longitudinally outwardly beyond a transverse portion forming an open-ended recess and an opposite closed end and provided with a transverse swivel handle connector spaced intermediate said ends, said mop body including superposed upper and lower walls having finger portions extending outwardly at one end thereof from a transverse end portion forming an open-ended recess and being secured together at marginal edges to form a main pocket and finger pockets extending from one end thereof, said

upper wall provided with an enlarged central opening for a mop handle disposed intermediate its ends and a slit connected to and extending longitudinally away from said central opening to its opposite end opening and cooperating therewith to facilitate insertion of said frame in said pocket with the fingers thereof in said finger

5 pockets and said handle connector below said central opening and disposed intermediate the ends of the body, and said body provided with thrums extending outwardly from the marginal edges thereof.

FLOYD T. PETTY.
